UNITED STATES PATENT OFFICE.

WILLIAM J. SMITH, OF NEW YORK, N. Y., ASSIGNOR TO EDWARDS & COMPANY, A CORPORATION OF NEW YORK.

ELECTRIC BELL.

1,216,743.

Specification of Letters Patent. Patented Feb. 20, 1917.

Application filed March 13, 1913. Serial No. 753,919.

To all whom it may concern:

Be it known that I, WILLIAM J. SMITH, a citizen of the United States, residing at New York, in the borough of Manhattan and 5 State of New York, have invented certain new and useful Improvements in Electric Bells, of which the following is a full, clear, and exact description.

This invention relates to improvements in 10 electric bells, the main object of the invention being to provide a bell which will operate successfully on an alternating current circuit. In the electromagnetic bells using alternating current it has been found to be 15 difficult to construct a bell which will operate in rhythm with the cycles of alternating current and especially is this true where the bell is attached to an alternating current line of as high a frequency as is used for 20 ordinary commercial purposes, which is generally of 60 cycles. I have found that by controlling the stroke of the hammer of an alternating current bell in a certain manner it will operate as regularly on alternating 25 current as on direct and my invention consists essentially in positively limiting the back stroke of the hammer and also in limiting the back stroke with relation to the action of the circuit interrupter. Another 30 object of the invention is to construct a yielding connection between the hammer and the armature which will also have the added function of preventing the armature from sticking. Other objects of the invention will 35 be apparent from the specification and claims hereinafter set forth, wherein—

Figure 1 is a sectional view of the bell, one of the coils of the electromagnet being removed;

40 Fig. 2 is an enlarged sectional detail view showing the hammer or plunger in contact with the bell; and

Fig. 3 is a view of that face of the armature which is adjacent the poles of the magnet and looking downward in Fig. 2, the 45 hammer and bearings of the armature being in section.

Referring to the drawing, 1 represents a gong mounted on a post 2, which is supported on a base-plate 3 at one end thereof, the other end of the base-plate being attached to a casing 4 provided with a removable cover 5. The end 7 of the casing is made separate 55 from the main portion and has attached thereto the cores of the electromagnet 6,

the other end of these cores being joined together by means of a connecting plate 9 of brass or the like which is provided with lugs 10 bent at right angles to the plate—provided with openings through which the trunnions of the armature 11 pass, as clearly shown in Fig. 3. Attached to the armature 11 is a plate made of resilient material such as hardened copper, which plate is fastened to the armature by the rivet 13. The middle portion of the upper end of the plate is cut away as at 14 and the parts of the plate on each side of the same are bent to form cylindrical bearings 15 which support the pin 16, which is fitted in an opening in the reciprocating plunger or hammer 17, the other end of this hammer sliding through an opening in the end 7 of the casing provided for that purpose. The ends of the pin 16 are bent to prevent undue longitudinal movement thereof. The plate 12 has two extensions or arms 18 which are so positioned as to come in contact with the cores of the electromagnet when the armature is in its attracted position and so prevent the same from sticking. By making these arms integral with the resilient plate 12, they aid in returning the spring plate to its normal position against the armature after the same has been moved forward due to the inertia of the plunger 17 attached thereto. The armature 11 carries an arm 19 which is fastened to but insulated from the same and carries at its free end a carbon contact 20 which forms a part of the interrupter, hereinafter referred to. The lower edge of the armature is provided with a lug through which a swiveled eye 21 passes. A spring 22 is connected at one end to the eye and at the other end is connected to a screw 23 whereby the tension of the spring which holds the armature normally away from the electromagnet, may be regulated. A second carbon contact 24 of the interrupter is carried on an arm 25 which is fastened to but insulated from the connecting plate 9. A set-screw 26 is inserted in the rear of the casing and acts as a back-stop to limit the rearward travel of the reciprocating plunger 17. A similar set-screw is shown at 27 which is provided with an insulated end and is used to adjust the relative position of the contacts 20 and 24, to insure the proper control of the circuit. The back stop 26, being adjustable it is possible to so regulate the stroke 110

of the reciprocating plunger or hammer that the period of vibration of the same will be in rhythm with the oscillations of alternating current used and produces an alternating current bell which strikes as regularly and continuously as if direct current were used. This stop 26 positively stops the hammer shortly after the circuit contacts have come together on the back stroke of the armature and it has been found that the best operation of the bell depends somewhat upon the relative adjustment of the contacts and back stop. Current for the bell enters through the binding-post 28 from which it passes through the coils of the electromagnet 6 to the insulated arm 25, contacts 24 and 20, arm 19, which is insulated from the armature, and out through a binding-post connected to the frame but insulated therefrom (not shown).

Claims:

1. An electromagnetic bell comprising an armature, a resilient plate attached thereto, a hammer connected with said plate, the inertia of the hammer moving the spring-plate away from the armature to permit the hammer to strike the bell when the armature is moved to its attracted position, said plate having at least one arm which engages with the core of the electromagnet when the armature is in its attracted position to prevent the same from sticking, said arm being resilient to aid the spring-plate to return to its normal position against the armature.
2. An electric bell comprising a casing, a gong carried by said casing, an electro-magnet in said casing, an armature for said electro-magnet, a spring exerting its tension to draw said armature away from the core of the electro-magnet, a reciprocating hammer having one end thereof projecting through an opening in said casing, the walls of said opening forming a bearing for said hammer, an adjustable stop for limiting the rearward travel of said hammer, an interrupter comprising a stationary contact, means for adjusting the position of said contact, a movable member carried by said armature, a plate mounted on said armature, a connection between said plate and said hammer, and said plate having a part of non-magnetic material interposed between

the core of the electro-magnet and its armature.

3. An electric bell comprising a casing, a gong carried by said casing, an electro-magnet in said casing, an armature for said electro-magnet, a spring exerting its tension to draw said armature away from the core of the electro-magnet, means for adjusting the tension of said spring, a reciprocating hammer having one end thereof projecting through an opening in said casing, the walls of said opening forming a bearing for said hammer, an adjustable stop for limiting the rearward travel of said hammer, an interrupter comprising a stationary contact, means for adjusting the position of said contact, a movable member carried by said armature, a plate mounted on said armature, a connection between said plate and said hammer, and said plate having a part of non-magnetic material interposed between the core of the electro-magnet and its armature.

4. An electric bell comprising a casing, a gong carried by said casing, an electro-magnet in said casing, an armature for said electro-magnet, a spring exerting its tension to draw said armature away from the core of the electro-magnet, a reciprocating hammer having one end thereof projecting through an opening in said casing, the walls of said opening forming a bearing for said hammer, an adjustable stop for limiting the rearward travel of said hammer, an interrupter comprising a stationary contact, means for adjusting the position of said contact, a movable member carried by said armature, a plate mounted on said armature, a connection between said plate and hammer, said connection comprising a pin passing through said hammer and lugs on said plate bent around the ends of said pin, and said plate having a part of non-magnetic material interposed between the core of the electro-magnet and its armature.

In witness whereof, I subscribe my signature, in the presence of two witnesses.

WILLIAM J. SMITH.
